SECONDARY AIR CONTROL FOR FURNACES

Philip O. Henderson, Washington, D. C., assignor
of one-third to John O'Dea and one-third to
B. Earl Wenger, both of Washington, D. C.

Application May 4, 1937, Serial No. 140,750

12 Claims. (Cl. 158—28)

My invention relates to control means for secondary air supplied to furnaces, especially furnaces provided with burners operating on oil, gas or pulverulent solid fuel.

5 The invention provides a plentiful and regulated supply of secondary air and incorporates means for preventing emission of products of combustion through the secondary air supply opening whenever for any reason back pressures 10 develop in the firebox. In one form of embodiment the invention incorporates means for making the rate of supply of secondary air responsive to any suitable high-low flame control used with the furnace, and a preferred form of embodiment contemplates the use of closure means in the secondary air supply passage responsive to back pressures to close the passage and responsive to the high-low flame control partially to 15 close the passage.

20 In burners for fluid and analogous fuel, primary air is of course mixed with the fuel supplied to the burner, and to support complete and most efficient combustion generous quantities of secondary air are also required. This 25 secondary air is commonly admitted in part adjacent the burner, but more particularly and in larger quantities below the burner. For example, in furnaces which have been converted from coal burners to oil or gas burners, the ash 30 removal door in the lowermost part of the front wall below the level of the grate is kept open, or a shutter in it is kept open, to admit most of the secondary air required, the remainder being supplied through an opening in the furnace wall 35 around or adjacent the burner nozzle.

It sometimes happens that downdrafts occur during burner operation, and it rather frequently happens that backfires take place in the firebox, producing sudden and sometimes violent increases in pressure in the firebox and flue and of course at the secondary air inlet. Both downdrafts and backfires thus have the effect of reversing the flow at the secondary air inlet, so that the gaseous contents of the firebox tend 40 to issue through that inlet into the room or building containing the furnace. This is manifestly objectionable, particularly in the case of backfires, because in such cases the gases discharged into the room are generally the products of incomplete combustion, frequently high in carbon monoxide and almost invariably heavily soot-laden. An object of the present invention 45 is to provide means associated with the secondary air inlet to prevent such discharges without in any way interfering with the function of the

inlet to admit secondary air during normal operation of the furnace and burner.

A related object of the invention is to relieve the pressures against the described closure means when backfires of unusual violence occur, so that 5 damage to the parts is avoided.

The high-low flame control usually employed with oil and gas burners, particularly in the larger installations, comprises means responsive to boiler or other temperatures or pressures for 10 regulating the flame size so that overheating is prevented and so that during periods when high heat generation is not required the boiler will be fired by a flame of reduced size. The present invention cooperates with such a control by regulating the rate of supply of secondary air in accordance with flame size, so that the required 15 quantities of secondary air are supplied for the various flame sizes and particularly so that excessive quantities of air are not admitted to the 20 firebox when the flame is low. Thus, undesired cooling of the firebox is prevented.

Other objects of the invention are to provide means for the purposes specified which shall be simple, inexpensive, reliable and foolproof in operation, and entirely devoid of upkeep cost. 25 Further objects and advantages will appear from the description hereinafter of a preferred embodiment of the invention.

In the accompanying drawings, which illustrate 30 a preferred embodiment which has been found reliable and satisfactory in actual use, and which has therefore been selected as illustrative of the principles of the invention and not to limit the scope of the invention to the details disclosed. 35

Figure 1 is a vertical sectional view through a portion of a furnace front wall with which an embodiment of the invention is associated;

Fig. 2 is a front elevational view of the parts shown by Fig. 1;

Fig. 3 is a horizontal sectional view through the secondary air inlet duct, taken on the line 3—3 of Fig. 1;

Fig. 4 is a vertical section through the duct at its inlet end, taken on the line 4—4 of Fig. 3; 45

Figs. 5 and 6 are detail views showing the latch by which the safety doors are yieldingly held in closed position on the shutters; and

Figs. 7 and 8 are detail sectional views showing the connecting duct or riser by which the two 50 secondary air inlet openings are placed in communication.

In the drawings, 1 designates a furnace, shown as a comparatively large type used to fire a steam boiler, but intended to be typical of any kind 55

of heating furnace. The furnace is provided with a wall 2, conveniently the front wall, having an opening 3 through which extends the nozzle 4 of a burner 5 operating on oil, gas, pulverized coal or the like. Preferably below the furnace, and below the grate 6 thereof, the wall 2 contains an additional opening 7, which constitutes the main inlet for secondary air, certain quantities of secondary air being admitted through the opening 3. It is to be understood that the foregoing arrangement is old and conventional and has proved unsatisfactory in use because downdrafts and backfires in the firebox cause products of combustion to be discharged through the openings 3 and 7 into the room containing the furnace. The structure which will now be described comprises the arrangement proposed by the present invention to prevent these discharges from the firebox into the room containing the furnace.

Fastened to the furnace wall 2 so as to surround the opening 7 is a secondary air inlet duct 8, conveniently in the form of a sheet metal box housing open at its front or inlet end 9. Within the duct 8 I provide closure means for the duct, normally open to admit air from the inlet end 9 to the discharge end 10 adjacent the furnace wall, as shown by the solid line arrows in Fig. 3, but adapted to close in response to back pressures tending to cause gas to flow from the firebox through the duct in the direction of the dotted line arrows of Fig. 3. This closure means comprises shutters 11 mounted relatively near the inlet end 9 of the duct, as by being hinged on the mounting plate 12 arranged vertically in the duct at about its center, so that the shutters may swing outwardly in response to back pressure and close against the duct side walls, so that the duct is more or less completely closed by the shutters 11 or by the shutters 11 and their mounting plate 12.

The shutters 11 are normally in the open position shown by the solid lines in Fig. 3. In this position they rest against the adjustable stops 13 mounted on a wall of the duct, and they are biased to this open position by the incoming current of air or by some positive biasing means. The turning axis of each shutter may be inclined slightly, or light springs may be used, if positive biasing is desired. In either event, in open position the shutters make obtuse angles with the mounting plate 12, so that they form the converging sides of a pocket opening in the direction from which reverse flow will move when back pressure occurs, all as shown in Fig. 3.

If the closure means comprised only the shutters 11, a considerable amount of the gaseous contents of the firebox would pass out of the duct before the shutters 11 would move to their dotted line position to close the duct, and in the case of incomplete combustion a great deal of soot would be emitted to the room.

In order to make the closure means sufficiently sensitive and quick acting to close before much or any of the gaseous contents of the firebox pass out of the duct, I include as part of the closure means a second pair of shutters 14, arranged relatively near the discharge end 10 of the duct. These shutters are pivoted on hinges 15 spaced apart transversely of the duct and closed, either under the influence of incoming air or by some positive biasing means, against the adjustable stops 16 which are in general like the stops 13. In their normal, open posi-

tion, shown by full lines in Fig. 3, the shutters 14 form a pocket with its walls converging in the direction of its bottom, and its bottom opening between the pivots 15. In their closed position the shutters 14 engage the side walls of 5 the duct, and it will be understood that the shutters 14 swing on their pivots 15 to assume closed position as soon as back pressure occurs in the duct. Having moved to closed position, the back pressure is directed through the partially closed duct, between the pivots 15 into the pocket formed by the still open shutters 11. These shutters 11 thereupon promptly move to closed position, as shown by the dotted lines in Fig. 3, and the duct becomes completely closed. 15 It is to be observed that the duct and lower part of the firebox are normally filled with fresh air. When reverse flow occurs it is this fresh air which actuates the shutters 14 and in prompt succession the shutters 11. Flow past 20 the several shutter means and out through the inlet end 9 of the duct is thus of fresh air only, so that soot and other products of combustion are not discharged into the room containing the furnace. This feature of the invention I regard 25 as of great importance.

It will be appreciated that with the duct closed as has been explained the gases in the firebox will normally be released through the smoke flue. However, it sometimes happens, in the case 30 of comparatively violent explosions at the burner or elsewhere in the firebox, that sufficiently high pressures are generated to disrupt the parts. To prevent damage in such cases I provide safety doors 17 in the shutters 14 and similar safety 35 doors 18 in the shutters 11. In a preferred form of embodiment the shutters take the form of open frames and the safety doors are imperforate plates spring pressed to close these open frames. The safety doors are hinged to the 40 shutters opposite the ends of the shutters which are pivoted in the duct. Opposite their hinges the safety doors are latched to the shutters preferably by an adjustable means like that shown at 19 in Fig. 6, so that the safety doors may be 45 made openable by an adjustable, predetermined pressure applied to them. The means 19, as shown, comprises an adjusting screw carrying a spring latch element bearing against the free end of the safety door and holding the door 50 against its shutter with a pressure determined by the adjustment of the screw in its mounting. Obviously, other types of latch might be substituted.

In the case of a backfire of predetermined violence, the shutters swing to closed position and the safety doors swing free of the latches and lie against the side walls of the duct, as shown in the case of the doors 17 in dotted lines in Fig. 3. The doors 18 open in the same manner. 60

As has been explained, it is customary to admit a portion of the secondary air through the opening 3 or elsewhere in the immediate vicinity of the flame. Ordinarily, this secondary air is admitted directly from the room and passes between the fan housing 50 and burner front plate 51, and thence through a jacket within the burner nozzle 4. In order to prevent emission of gas from the firebox through this secondary air path and into the room containing the furnace, 65 I provide a duct connecting this secondary air inlet with the duct 8, so that secondary air taken in at the nozzle 4 must enter the inlet end 9 of duct 8 and pass through duct 8. This arrangement requires reverse flow through the upper 70

inlet to be directed into the duct 8, where it is trapped by the closing of the shutters, so that gases passing out of the furnace through the upper inlet are not admitted to the room containing the furnace.

A suitable arrangement to accomplish this purpose consists in a connecting duct 20 rising from an opening in the top wall of the duct 8 and extending to the burner 5. An inverted U-shaped flange 21 fills the space between the fan housing 50 and the burner front plate 51, and this flange is connected to the riser duct 20 so that the upper secondary air inlet is isolated from direct connection with the outer air and can only be supplied with air admitted through the duct 8, the connecting duct 20 and the space surrounding the upper inlet and defined by parts 50, 51 and 21.

By the instrumentalities hereinabove described, it will be obvious that outflow from the firebox will be constrained to pass through the duct 8, which will become closed before soot or the like reaches the shutters 11.

It is customary to provide furnaces having oil, gas or analogous burners with a high-low flame control. This control functions to turn the flame down in response to predetermined temperatures or pressures in the boiler. A conventional showing of such a control is designated 22 in Figs. 1 and 2, wherein the weighted arm 23 rises in response to a predetermined temperature or pressure in the boiler and the consequent pull on the chain 24 lifts the weighted arm 25 partially to close the primary air control valve 26 in the burner 5 and partially to close the oil supply valve 27 which is operated through some such linkage system as that shown in Figs. 1 and 2. It is desirable, when the high-low flame control moves to reduce the flame, correspondingly to reduce the input rate of secondary air. My invention is admirably adapted to be used in co-operation with a high-low flame control and an illustrative embodiment of one manner of effecting such cooperation is shown in Figs. 1 and 2. The primary air control valve rod 25 is extended and its free end pulls a depending chain 28 which elevates and lowers a weighted rod 29 fast on the end of a rotatable rod 30 which extends through the mounting plate 12 for the shutters 11 and carries at its inner end a specially formed double cam 31, surfaces of which engage the shutters 11. The double cam may take the form of a straight rod set at an inclination to the vertical, or it may be a rod having opposite angularly directed ends. In any event the arrangement is such that rotation of the rod 30 tends to spread the shutters 11 outwardly. It will be noted that a particular advantage of the arrangement described resides in the fact that the shutters 11 are moved toward closed position by rotation of the rod 30 in either direction, so that the rod 29 and chain 28 may be disposed on the right-hand side or the left-hand side of the rod 30. In this way the device may be incorporated in different furnace installations regardless of the location of the high-low flame control.

It will be appreciated that when the high-low flame control moves to reduce the flame size the shutters 11 are correspondingly moved toward closed position to constrict the opening through duct 8 and correspondingly reduce the rate of admission of secondary air.

From the foregoing explanation it is evident that the invention contemplates simple and ef-

fective means to attain the objects specified in the introduction to the specification. It is to be understood that the construction described has been selected merely to exemplify the invention and not to limit it to the details shown. The invention is capable of embodiment in other and modified forms, and all such modifications, to the extent that they incorporate the principles of the invention as defined by the appended claims, are to be deemed within the scope and purview thereof.

I claim:

1. In an air admission and control apparatus for a furnace, a duct adapted to convey combustion air to the furnace, and closure means in said duct normally open and adapted to close upon the occurrence of reverse flow of gases through the duct, said closure means comprising shutter means relatively near the inlet end of the duct movable to close the duct and second shutter means relatively near the discharge end of the duct movable by said reversely flowing gases partially to close the duct to direct said gases against the first named shutter means to close the same.

2. In an air admission and control apparatus for a furnace, a duct adapted to convey combustion air to the furnace, and closure means in said duct normally open and adapted to close upon the occurrence of reverse flow of gases through the duct, said closure means comprising a pair of shutters hinged in the duct relatively near its inlet end and movable to close the duct, and a second pair of shutters hinged in the duct relatively near its discharge end on axes spaced apart transversely of the duct, said second pair of shutters being movable by said reversely flowing gases partially to close the duct to direct said gases between the spaced axes and against the first named shutters to close the same.

3. In an air admission and control apparatus for a furnace, a duct adapted to convey combustion air to the furnace, and closure means in said duct normally open and adapted to close upon the occurrence of reverse flow of gases through the duct, said closure means comprising shutter means relatively near the inlet end of the duct, biased to open position and movable to close the duct, and second shutter means relatively near the discharge end of the duct, biased to open position and movable by said reversely flowing gases partially to close the duct to direct said reversely flowing gases against the first named shutter means to close the same.

4. In an air admission and control apparatus for a furnace, a duct adapted to convey combustion air to the furnace, closure means in said duct normally open and adapted to close upon the occurrence in the duct of reverse flow of gases due to pressures within a predetermined range, said closure means comprising shutter means relatively near the inlet end of the duct movable to close the duct, second shutter means relatively near the discharge end of the duct movable by said reversely flowing gases partially to close the duct to direct said gases against the first named shutter means to close the same, and safety means in the first named shutter means openable in response to reverse flow due to pressures above those in said range to open the duct.

5. In an air admission and control apparatus for a furnace, a duct adapted to convey combustion air to the furnace, closure means in said duct normally open and adapted to close upon the occurrence in the duct of reverse flow of

- gases due to pressures within a predetermined range, said closure means comprising shutter means relatively near the inlet end of the duct movable to close the duct, second shutter means relatively near the discharge end of the duct movable by said reversely flowing gases partially to close the duct to direct said gases against the first named shutter means to close the same, and safety means in each of the shutter means openable in response to reverse flow due to pressures above those in said range to open the duct.
6. In an air admission and control apparatus for a furnace, a duct adapted to convey combustion air to the furnace, closure means in said duct normally open and adapted to close upon the occurrence in the duct of reverse flow of gases through the duct, said closure means comprising shutter means relatively near the inlet end of the duct movable to close the duct, second shutter means relatively near the discharge end of the duct movable by said reversely flowing gases partially to close the duct to direct said gases against the first named shutter means to close the same, and adjustable stop means associated with at least one of said shutter means for determining the open position thereof.
7. In an air admission and control apparatus for a furnace, a duct adapted to convey combustion air to the furnace, closure means in said duct normally open and adapted to close upon the occurrence in the duct of reverse flow of gases through the duct, said closure means comprising shutter means relatively near the inlet end of the duct movable to close the duct, second shutter means relatively near the discharge end of the duct movable by said reversely flowing gases partially to close the duct to direct said gases against the first named shutter means to close the same, and adjustable stop means associated with each of said shutter means for determining the open position thereof and the air capacity of the duct.
8. In an air admission and control apparatus for a furnace, a duct adapted to convey combustion air to the furnace, closure means in said duct normally open and adapted to close upon the occurrence in the duct of reverse flow of gases due to pressures within a predetermined range, said closure means comprising shutter means relatively near the inlet end of the duct movable to close the duct, and second shutter means relatively near the discharge end of the duct movable by said reversely flowing gases partially to close the duct to direct said gases against the first named shutter means to close the same, the first named shutter means comprising a door frame and a door normally engaged therewith, said frame and door being normally movable together, said door being movable away from the door frame to open the duct in response to reverse flow due to pressure above those in said range.
9. In an air admission and control apparatus for a furnace, a duct adapted to convey combustion air to the furnace, closure means in said duct normally open and adapted to close upon the occurrence in the duct of reverse flow of

gases due to pressures within a predetermined range, said closure means comprising shutter means relatively near the inlet end of the duct movable to close the duct, and second shutter means relatively near the discharge end of the duct movable by said reversely flowing gases partially to close the duct to direct said gases against the first named shutter means to close the same, each of said shutter means comprising a door frame and a door normally engaged therewith, said frame and door being normally movable together, said door being movable away from the door frame to open the duct in response to reverse flow due to pressures above those in said range.

10. In a furnace, a burner, high-low flame control means therefor, a duct adapted to convey secondary air to the furnace, closure means in said duct normally open and adapted to close upon the occurrence of reverse flow of gases through the duct, said closure means comprising shutter means relatively near the inlet end of the duct movable to close the duct and second shutter means relatively near the discharge end of the duct movable by said reversely flowing gases partially to close the duct to direct said gases against the first named shutter means to close the same, and means engageable with said closure means and responsive to said high-low flame control means for regulating the open position of said closure means.

11. In a furnace, a burner, high-low flame control means therefor, a duct adapted to convey secondary air to the furnace, closure means in said duct normally open and adapted to close upon the occurrence of reverse flow of gases through the duct, said closure means comprising shutter means relatively near the inlet end of the duct movable to close the duct and second shutter means relatively near the discharge end of the duct movable by said reversely flowing gases partially to close the duct to direct said gases against the first named shutter means to close the same, and means engageable with the first named shutter means and responsive to said high-low flame control means for regulating the open position of said first named shutter means.

12. In a furnace, a burner, high-low flame control means therefor, a duct adapted to convey secondary air to the furnace, closure means in said duct normally open and adapted to close upon the occurrence of reverse flow of gases through the duct, said closure means comprising a pair of shutters hinged in the duct relatively near its inlet end and movable to close the duct and second shutter means relatively near the discharge end of the duct movably by said reversely flowing gases partially to close the duct to direct said gases against the first named shutter means to close the same, and means for regulating the open position of said closure means comprising a member pivoted between said pair of shutters and movable in response to said high-low flame control means to engage said shutters.

PHILIP O. HENDERSON.
